REMOTE TUNING SYSTEM FOR RADIO RECEIVERS

Hans Bauer, New York, N. Y.

Application September 6, 1935, Serial No. 39,484

6 Claims. (Cl. 250—20)

This invention relates to a remote tuning system for radio receivers, and more particularly to a remote tuner, designated as a tele-tuner, which may be associated with a radio receiver for the control thereof from a remote point.

It is the object of my invention to provide a remote tuning unit which may be connected to an existing radio-receiver installation in a most simple manner without modifying any connections other than the mere attachment of the lead from the tuning unit to any point of the lead-in from the receiving antenna to the radio-receiver.

It is a further object of my invention to provide a compact tuning circuit to which the incoming broadcast energy is shunted, at which point it is mixed with a local source of oscillations to obtain a carrier wave of a predetermined frequency, preferably beyond the normal broadcast range, to which the radio-receiver is permanently tuned. This carrier wave with the signal energy thereon, obtained by the concomitant operation of the local oscillator with the tuning circuit for the incoming broadcast energy, is conducted to the radio-receiver for the demodulation of the signals therefrom.

My invention contemplates a novel form of a coupling radio-frequency transformer composed of three windings wherein the primary winding for the incoming broadcast energy serves at the same time as the secondary winding for the output energy from the mixer circuit whence it is conducted to the radio-receiver.

It is a further object of my invention to provide a self-contained tuning unit remote from the radio-receiver which may be energized from any commercial source of electric energy.

Other objects and purposes will appear from a more detailed description of one preferred embodiment of the invention following hereinafter, taken in conjunction with the accompanying drawing, wherein,

Fig. 1 is a diagrammatic view of the general application of the invention;

Fig. 2 is a circuit diagram of the remote tuning unit, and

Fig. 3 is a front elevation with certain parts in section of the novel coupling transformer forming part of my invention.

In Fig. 1 is shown any conventional type of radio-receiver which is permanently tuned to a predetermined frequency, preferably beyond the normal broadcast band. In the legend applied to Fig. 1, the receiver is shown tuned below the lower end of the broadcast band, at a frequency

of 525 k. c. Connections are shown from the terminals of the receiver to the ground G and the lead-in A from the signal receiving means. The lead B from the remotely situated tele-tuner T is connected to any point along the lead-in A. The plug M is plugged into any commercial 110 volt main of electric energy, either A. C. or D. C., for energizing the remote tuning unit.

The incoming broadcast energy is shunted from the radio-receiver along the lead B which is connected to the primary winding L1 of the radio-frequency transformer having L2 for its secondary winding. The selection of the incoming energy is effected by adjusting condenser C1 having associated therewith the trimming condenser C4.

A compact unit is obtained by using a single tube, for example type 6A7, for performing all of the desired functions. The energy required for operating this tube is derived from the power main by the connection of the plug M thereto. A rectifier tube, type 37, may be utilized for obtaining the necessary direct current potentials required by the pentagrid converter 6A7. Upon the closing of switch 12, a circuit is completed from one side of the line through resistor 14, heaters 15 and 16 of the two tubes, and fuse 13 to the other side of the line. Resistor 14 limits the current value through the heaters to the required 0.3 ampere. The energy which may be rectified by tube 37 is filtered by a condenser-input type 30 filter and is imposed as direct current energy at the bus wires 18 and 19. Conductor 30 leads from bus 18 and is connected through the winding L5 and conductor 31 to the plate of 6A7. The second grid of the tube is connected to lead 22 and functions as the plate of the local oscillator. Lead 22 contains the tickler coil L3 and is connected to the bus 18. The input circuit of the local oscillator is comprised by the coil L4 and variable condenser C2 and has associated therewith the padding condenser C3 for tracking the oscillator with the modulator.

The incoming broadcast energy is applied to the control grid of 6A7 through lead 24, which grid is shielded by the combined action of the third and fifth grids of the tube, connected together to a common point at a potential lower than the plate by the voltage drop in resistor 32.

Resistor 25 biases the oscillator grid, and the resistor 26 biases the modulator grid. In conjunction with the latter there is a variable potentiometer resistance P associated as well with the transformer L1—L2, which is used for controlling the gain of the tuning device and consequently the volume of the receiver.

In operation, for the given example, the local oscillator must be tuned 525 k. c. higher than the modulator. Thus if reception of a station at 700 k. c. is desired, L2 and C1 must be tuned to 5 700 k. c. and the local oscillating circuit, L4 and C2, to 1225 k. c. producing a beat frequency equivalent to the difference between these frequencies.

Fig. 3 shows the physical arrangement of coils L1, L2 and L5 shown schematically in Fig. 2. 10 The incoming broadcast energy arrives over wire B to primary winding L1 which is coupled to the secondary winding L2, forming part of the incoming modulating circuit. The output circuit associated with the plate of 6A7, composed 15 of C5 and L5, is tuned to the frequency of the radio-receiver, and the coil L5 operates as a primary winding for the secondary L1 to return the signal energy upon a carrier wave of said last-mentioned frequency over the wire B to the radio- 20 receiver.

The tele-tuner may be completely shielded as indicated in dotted lines in Fig. 2. By-pass condensers are provided at suitable points to obtain desired results in a manner well known in 25 the art.

While I have described my invention as embodied in concrete form and as operating in a specific manner for purposes of illustration, it should be understood that I do not limit my invention thereto, since various modifications will 30 suggest themselves to those skilled in the art without departing from the spirit of my invention, the scope of which is set forth in the annexed claims.

35 What I claim is:

1. In combination with a radio receiver tuned to a predetermined frequency, signal receiving means for the incoming broadcast energy connected with said radio receiver, control means remote from said radio receiver connected with 40 said signal receiving means through the intermediary of a single transmission conductor, said control means including a frequency converter device and said device comprising a unitary thermionic tube having a plurality of grids, means connected to two of said grids for generating a local source of oscillations of variable frequency, a radio-frequency transformer for impressing the incoming broadcast energy 45 upon another one of said grids composed of a primary winding connected to said signal receiving means and a secondary winding connected to said last-mentioned grid, an output circuit connected with said tube and adapted to 50 have produced therein the resultant of the local source of oscillations with the incoming broadcast energy tuned to said predetermined frequency, said output circuit including a high frequency transformer having for its secondary winding 55 the primary winding of said first-mentioned transformer, said last-mentioned winding being connected to said radio receiver through the intermediary of said transmission conductor, said transmission conductor being aperiodic whereby 60 to conduct efficiently the incoming broadcast energy in one direction and the signal energy at said predetermined frequency in the opposite direction.
2. In combination with a radio receiver tuned 65 to a predetermined frequency beyond the broadcast range, signal receiving means for the incoming broadcast energy connected with said radio receiver, readily portable control means remote from said radio receiver connected with

said signal receiving means over a single transmission conductor adapted to transmit the incoming broadcast energy in one direction and the signal energy superposed upon a carrier wave of said predetermined frequency in the opposite 5 direction, said portable control means including a frequency converter device, said device comprising a unitary thermionic tube having an electron-emitting element, a plurality of grids and a plate, means associated with two of said grids 10 for generating a local source of oscillations of variable frequency, a radio-frequency transformer for impressing the incoming broadcast energy upon another one of said grids composed of a primary winding connected to said transmission conductor and a secondary winding connected to said last-mentioned grid, an output circuit tuned to said predetermined frequency 15 connected with said plate having combined there- 20 in the local source of oscillations with the incoming broadcast energy, said last-mentioned circuit embodying a primary winding of a radio-frequency transformer having as a secondary winding therefor the primary winding of said first-mentioned radio-frequency transformer and said 25 single transmission conductor adapted to conduct the energy of said output circuit to said radio receiver for deriving the signals therefrom.

3. In combination with a radio receiver tuned 30 to a predetermined frequency, signal receiving means for the incoming broadcast energy connected with said radio receiver, control means remote from said radio receiver, a conductor extending from between said first means and said receiver to said control means, said control means including a frequency converter device, said device comprising means for generating a local source of oscillations of variable frequency, means for combining the incoming broadcast energy therewith, and an output circuit to obtain 35 the signal energy upon a carrier wave of said predetermined frequency, said output circuit being connected to said conductor for transmitting said last-mentioned carrier wave to said radio receiver for the demodulation of the signals 40 therefrom, said conductor having a transmission characteristic adapted to the efficient transmission of the incoming broadcast energy in one direction to said control means and the transmission of the carrier wave of said predetermined frequency in the opposite direction 45 from said control means to said radio receiver.

4. In combination with a radio receiver tuned 50 to a predetermined frequency, signal receiving means for the incoming broadcast energy connected with said radio receiver, control means remote from said radio receiver, a conductor extending from between said first means and said receiver to said control means, said control 55 means including a frequency converter device, said device comprising means for generating a local source of oscillations of variable frequency, means for combining the incoming broadcast energy with said oscillations including a radio-frequency transformer having the primary winding 60 thereof connected to said conductor, and an output circuit to obtain the signal energy upon a carrier wave of said predetermined frequency embodying a winding operating as a primary 65 winding with respect to said first-mentioned winding which operates as a secondary winding for the carrier wave of said predetermined frequency, said last-mentioned winding operating 70 to transmit said carrier wave through the inter- 75

mediary of said conductor to said radio receiver for the demodulation of the signals therefrom and said conductor having an aperiodic characteristic whereby to transmit efficiently the incoming broadcast energy in one direction to said control means and the carrier wave of said predetermined frequency in the opposite direction from said control means to said radio receiver.

5. In combination with a radio receiver tuned to a predetermined frequency, signal receiving means for the incoming broadcast energy connected with said radio receiver, control means remote from said radio receiver, a conductor extending from between said first means and said receiver to said control means, said control means including a frequency converter device, said device comprising means for generating a local source of oscillations of variable frequency, means for combining the incoming broadcast energy therewith including a thermionic device and a radio-frequency transformer having the primary winding thereof connected to said conductor and the secondary winding thereof connected to said thermionic device, and an output circuit to obtain the signal energy upon a carrier wave of said predetermined frequency embodying a winding operating as a primary winding with respect to said first-mentioned primary winding which operates as a secondary winding for the carrier wave of said predetermined frequency, said last-mentioned winding operating to transmit said carrier wave through the intermediary of said conductor to said radio receiver for the demodulation of the signals therefrom and said conductor having an aperiodic

characteristic whereby to transmit efficiently the incoming broadcast energy in one direction to said control means and the carrier wave of said predetermined frequency in the opposite direction from said control means to said radio receiver. 5

6. In combination with a radio receiver tuned to a predetermined frequency beyond the normal broadcast range, signal receiving means for the incoming broadcast energy connected with said radio receiver, control means for the receiver situated remotely therefrom, a conductor extending detachably from between said first means and said receiver to said control means, said control means including a frequency converter device, said device comprising means for generating a local source of oscillations of variable frequency, means for combining the incoming broadcast energy therewith, including a radio-frequency transformer having the primary winding thereof connected to said conductor, and an output circuit to obtain the signal energy upon a carrier wave of said predetermined frequency, said output circuit including said primary winding and connected to said conductor 25 for transmitting said last-mentioned carrier wave to said radio receiver for the derivation of the signals therefrom, and said conductor having a transmission characteristic enabling efficient transmission of the incoming broadcast energy 30 in one direction to said control means and the transmission of the carrier wave of said predetermined frequency in the opposite direction from said control means to said radio receiver. 30
